FIG. 1

The design is characterized by the corner portions of the plate being disposed essentially in a plane parallel with the central portions of the plate.

I claim:

The ornamental design for a plate, substantially as shown and described.
